[57] CLAIM

The ornamental design for the portable computer housing, as shown and described.

DESCRIPTION

FIG. 1 is a top left front perspective view of a portable computer housing;

FIG. 2 is a top view of the portable computer housing;

FIG. 3 is a rear view of the portable computer housing;

FIG. 4 is a right view of the portable computer housing;

FIG. 5 is a front view of the portable computer housing;

FIG. 6 is a bottom view of the portable computer housing; and,

FIG. 7 is a perspective view of a second embodiment of the portable computer housing wherein the only difference in appearance is the omission of the speaker like pattern.

The left view is mirror to the right view.
